(57) CLAIM

The ornamental design for a shoe, as shown and described.

DESCRIPTION

FIG. 1 is a front perspective view of a shoe showing my new design;
FIG. 2 is a side view thereof; and,

FIG. 3 is a rear perspective view thereof.

The solid lines extending from the front and rear of the shaded area, along with the shaded area, form the claimed design. The broken lines depicting the remainder of the shoe form no part of the claimed design.
